US00D621468S

(12) **United States Design Patent**
Nilsson

(10) **Patent No.:** US D621,468 S
(45) **Date of Patent:** ** Aug. 10, 2010

(54) **PROJECTILE**

(75) Inventor: Åke Nilsson, Arvika (SE)

(73) Assignee: **Norma Precision AB**, Amotfors (SE)

(**) Term: **14 Years**

(21) Appl. No.: **29/327,452**

(22) Filed: **Nov. 6, 2008**

(30) **Foreign Application Priority Data**

Jun. 11, 2008 (EM) 000949177

(51) **LOC (9) Cl.** 22-03

(52) **U.S. Cl.** D22/116

(58) **Field of Classification Search** D22/115,
D22/116; 463/2; 102/501-510, 520; 86/19.5,
86/51-54

See application file for complete search history.
